UNITED STATES PATENT OFFICE.

CARL W. LARSON AND CARL OLOFSON, OF JAMESTOWN, NEW YORK, ASSIGNEES TO DAHLSTROM METALLIC DOOR COMPANY, OF JAMESTOWN, NEW YORK, A CORPORATION OF NEW YORK.

METALLIC DOOR AND THE LIKE.

1,171,443.

Specification of Letters Patent. Patented Feb. 15, 1916.

Application filed February 23, 1912. Serial No. 679,440.

To all whom it may concern:

Be it known that we, CARL W. LARSON and CARL OLOFSON, both citizens of the United States, and residents of Jamestown, in the county of Chautauqua and State of New York, have invented new and useful Improvements in Metallic Doors and the like, of which the following is a specification.

10 Our invention relates to metallic doors and the like, and it has for one of its objects, the provision of a door of this type in which the stiles and rails are made hollow and each formed of a single sheet of material and having an invisible seam at one of its corners.

Another object is the provision of simple and effective means for locking a panel to the stiles and rails without the use of rivets 20 and without welding the parts together.

Other objects are to so construct the door that water, dirt and other matter cannot enter at the seams or where parts are joined or connected and cause rust and eventually 25 destroy the material from which the door is made; to provide new and improved means for fastening a pane or panes of glass in the door, and to otherwise improve on the construction of metallic doors and 30 similar articles.

Our invention consists in the construction, formation, arrangement and connection of the various parts to be hereinafter described and particularly pointed out in the subjoined claims.

In the drawings, Figure 1 is a side elevation of a door constructed according to our invention. Fig. 2 is an enlarged vertical section taken on line *v*—*v*, Fig. 1. Fig. 40 3 is an enlarged broken vertical section taken on line *w*—*w*, Fig. 1. Fig. 4 is an enlarged horizontal section taken on line *x*—*x*, Fig. 1. Fig. 5 is an enlarged horizontal section taken on line *z*—*z*, Fig. 1.

45 Referring now to the drawings in detail, in which like numerals of reference refer to like parts in the several figures, the reference numerals 1, 2, designate the stiles of the door, 3 the top rail, 4 the intermediate 50 rail, and 5 the bottom rail. Bounded by the stiles and rails 3 and 4 is a glazed panel formed of two panes of glass 6, 7, separated by a mullion 8 and between the rails 4 and 5 is a panel 9. Each of the stiles and rails

is constructed of a single sheet of metal 55 bent or rolled upon itself to provide opposite side walls 10, 11, an inner edge wall 12, and an outer edge wall 13, the longitudinal marginal portions of the metal forming said stiles and rails being connected by an invisible seam at one of their four corners, the 60 seams of the stiles and the upper and lower rails being at one of the corners at their outer edges, while the seam of the intermediate rail may be at any of its four corners. 65

The invisible seams are preferably interlocking seams wholly within the areas of the stiles and rails and are formed by bringing the marginal portions of each sheet together 70 at one edge of the stile or rail, as the case may be, and bending one of the marginal portions inward, then laterally toward the nearest side wall, the other marginal portion being bent inward, thence laterally also 75 to the nearest side wall, thence outward in contact with said side wall and toward the edge wall from which it projects and finally laterally in a reverse direction so as to interlock with the first-mentioned marginal 80 portion. In this manner the opposite marginal portions of the sheets forming the stiles and rails are bent into reversely arranged channels or hook portions 14 which 85 interlock at one of the four angles created in each stile and rail.

The rails are placed between the stiles and riveted, welded, or otherwise fastened thereto and in the opposite longitudinal edges of the intermediate rail, the inner edges of the upper and lower rails, and the inner edges of the stiles, dove-tailed grooves or depressions 19 are formed by bending the metal 90 into channel-shape with its side walls preferably converging outward. 95

Although we have shown a glazed panel with means for fastening the panes of glass and a mullion between the panes of glass and also a metallic panel beneath the glazed panel and means for fastening it in place, 100 it is apparent that metallic panels may be used throughout the door, or a single glazed panel may be used if desired, as this would require merely the elimination of certain parts of our invention which can be readily done, as parts of our invention can be used with or without other parts as will be clearly understood from the following description. 105

As hereinbefore stated, the panes of glass 6, 7, constitute a glazed panel; and wherein hereinafter the term "panel" is used, it is to be understood as a general term covering either a glazed panel or a metallic or other panel, and as these panels are fastened to the stiles and rails, we will term the fastening means a "panel molding" and designate the same 15.

- 10 We resort to a slight change in construction for the panel molding used with glazed panels and metallic panels and shall separately designate each by numerals. The panel molding used for holding a pane or panes of glass in place, comprises two members 16, 17 which we shall term, respectively, a "backing molding" and a "fastening molding." Each length of the backing molding is formed of a single strip of sheet metal 18 bent or fashioned to provide a bearing wall 19 arranged parallel with the sides of the door, from which wall the strip of metal is bent transversely in opposite directions, as at 20, 21. An oblique wall 22, preferably 25 curved and bent to provide an ornamental surface, extends from the transverse wall 20 toward the inner edge of the stile or rail, where the metal forming the molding is continued laterally inward to provide a bearing 30 wall 23 which lies in contact with the stile or rail, and from which wall the metal is continued toward the edge of the door at an acute angle to lie in contact with one side wall of the depression in the stile, or rail, and thence laterally a short distance in contact with the inner wall of said depression. From the transverse wall 21 the metal is continued at an obtuse angle to enter the depression in the stile, or rail, and lie in 35 contact with its other side wall, and thence directed laterally in contact with the inner wall of said depression. The marginal portions of this sheet are therefore separated within the depression formed in the inner 40 edge of the stile or rail, and are somewhat yielding so that they can be pressed toward each other to permit of easily entering them within the depression and after relieving them from pressure, permit their separating 45 to impinge against the walls of said depressions. The backing molding is therefore of substantially tubular form and has a projecting spring portion which fits into the depression of the stiles and rails. A reinforcing bar 50 in the form of a metallic angle bar 24 is placed within the tubular backing molding to bear against the marginal portions thereof and hold them against inward pressure.
- 55 Each length of the fastening molding, which coacts with the backing molding, is formed of a strip of metal having a central ornamental portion 25 bent and rolled to provide an ornamental face wall and from 60 opposite edges of which project flanges 26,

27, which are arranged at right angles to each other; the flange 26 serving as a bearing wall which lies in contact with the inner edges of the stiles or rails, while the other bears against the pane of glass. Through 70 the ornamental facing-wall screws 28 are passed, that take into the backing molding and the angle bar located therein so that a pane of glass placed between the backing molding and fastening molding is securely 75 held in place.

The panel molding for holding the metallic panel 9 in place has each length formed of a strip of metal bent centrally into a channel 29 from the outer ends of the side 80 walls whereof the metal is directed outward at an angle and rolled and bent to form two ornamental walls 30, and thence inward at right-angles to the face of the door, as at 31, to form bearing walls which lie in contact with the inner edges of the stiles, or rails, and thence finally at acute angles to provide impinging walls 32 which terminate in opposite lateral extensions 33 to provide a spring projection 34 on the molding which fits into the dove-tail depression of the stile, or rail and may be sprung thereinto or inserted from either end of the stile or rail. Within the channel portions of the panel molding the marginal portions of two panel 95 plates 35, 36 are held with asbestos or other sound deadening and fire proof material interposed therebetween.

Having thus described our invention, what we claim is:

1. A metallic door or the like having hollow stiles and rails, each formed of sheet metal bent to provide side walls and an inner edge wall having a dove-tail depression, a panel molding comprising two parts, one 105 a backing molding and the other a fastening molding; a panel held between said backing and fastening moldings; said backing molding being formed of sheet metal having a backing wall, an oblique facing wall 110 extending from one edge of said backing wall and marginal portions entering said dove-tailed depression and bearing against the side and inner walls thereof and said fastening molding having an oblique facing 115 wall with marginal flanges arranged at right angles to each other and bearing respectively against the inner edge walls of said stiles and rails and against the panel, and means for securing said fastening molding 120 in place.

2. A metallic door comprising hollow stiles and rails having dove-tailed depressions in their inner edges, a panel bounded by said stiles and rails, and panel moldings 125 formed of strips of metal, one strip being bent into substantially tubular form with the marginal portions thereof entered into and fitting against the walls of said dove-tailed depressions and the other being bent to 130

provide a facing wall and two bearing walls arranged at right angles to each other and bearing respectively against the inner edge walls of said stiles and rails and said panel, 5 an angle bar fitting into the tubular molding to stiffen the same and hold the marginal portions thereof to said dove-tailed depressions, and screws passing through the fastening molding and taking into the tubular molding and the angle bar held therein.

3. A metallic door having hollow stiles and rails, each formed of a sheet of metal bent to provide side walls and an inner edge wall having a depression, a molding formed 15 of sheet metal bent into substantially tubular form to provide a backing wall and a

facing wall with the marginal portions of said metal bent at an angle to fit into said depressions, a panel placed against said molding, a fastening molding bearing 20 against the edges of said stiles and rails and against the panel, and screws passing through said fastening molding and taking into the tubular molding.

In testimony whereof, we have affixed our 25 signatures in the presence of two subscribing witnesses.
